R. H. BLOXHAM

TRACK LINER

Filed June 15, 1925

Inventor:

Ralph H. Bloxham,

By Cromwell, Greist & Warden

Atto.

Witness:

R. Burkhardt.

UNITED STATES PATENT OFFICE.

RALPH H. BLOXHAM, OF CHICAGO, ILLINOIS, ASSIGNOR TO CHICAGO STEEL FOUNDRY COMPANY, OF CHICAGO, ILLINOIS, A CORPORATION OF MAINE.

TRACK LINER.

Application filed June 15, 1925. Serial No. 37,155.

The principal object of the invention is to provide a track liner wherein the association between the base and the lever which fulcrums on the base is such that the liner is capable of shifting a rail a substantial distance without any change in the position of the base in the ballast at the side of the rail.

While the foregoing statement is indicative of the nature of the invention, other objects and advantages will be evident upon a full understanding of the features of construction and arrangement which constitute the invention.

A track liner embodying the invention is disclosed in the accompanying drawing and in the following description, but such embodiment is presented merely for the purpose of exemplification as the invention obviously is susceptible of embodiment in other structurally modified forms coming equally within the comprehensive scope of the appended claims.

In the drawing:

Fig. 1 is a side view of the track liner in operative position against a rail;

Fig. 2 is a rear view;

Fig. 3 is a top view;

Figs. 4, 5 and 6 are a series of side views showing one way in which the track liner may be used; and

Fig. 7 is a side view of a slightly modified form of the track liner.

It will be observed in the drawing that the track liner consists of a base 10 and a lever 11 which is fulcrumed on the base. The invention resides in the hereinafter described association between the base 10 and the lever 11 which permits the point of fulcruming to be changed at will when such a change is desirable, either because the rail has then been shifted too far from the initial point of fulcruming or because the ballast has permitted the base to recede unduly from the rail.

The base 10 is provided with an elongated bottom 12 which is adapted to seat upon the ballast or other supporting surface, and the bottom 12 is held against longitudinal movement in the ballast by a number of wide prongs 13 on the under surface of the bottom. The front end of the bottom 12 is bifurcated to form two laterally spaced lips 14 which are adapted to be inserted under the lower edge of the rail or other object

to be moved, and the under surface of the front end is preferably curved downwardly at 15 to give taper and additional body to the lips 14.

The bottom 12 of the base supports two longitudinally extending sides 16 which in turn support two laterally spaced bearing bosses 17 at points above the lips 14. Each of the bosses 17 is provided with two longitudinally spaced bearing apertures 18 and 19 of semi-cylindrical form which are connected from above by a slot 20 of arcuate form. The apertures 18 and 19 constitute two pairs of bearing seats in either of which the lever 11 may be pivotally mounted. A small web 21 extends upwardly from the bottom 12 at a forward inclination between the sides 16 at the rear ends of the lips 14, and forms with the bottom and the sides a socket into which the end of a crowbar or other suitable rod may be conveniently thrust in forcing the lips 14 of the base through the ballast into an operative position under the lower edge of the rail, as shown in Fig. 4.

The lever 11 is provided with a rail-engaging jaw 22 at its lower end, with a handle socket 23 at its upper end, and with two aligned fulcruming trunnions 24 intermediate its ends. The jaw 22 oscillates in the space between the lips 14 of the base 10, and may be advantageously corrugated to present a good gripping surface for engagement with the adjacent edge of the rail. The socket 23 is adapted to receive the end of a crowbar or other suitable rod, as shown in Fig. 5, whereby to present in the socket a handle which is of sufficient length to permit a great leverage to be applied to the rail through the jaw 22. The trunnions 24 are adapted to seat in either of the bearing apertures 18 or 19 of the bosses 17, and may be shifted from the rear bearing seats 18 to the front bearing seats 19 or vice versa, through the connecting slots 20, whereby to shift the fulcrum point of the lever 11 with respect to the base 10. The trunnions may consist of the ends of a pin which extends transversely through the lever and is fixedly positioned therein by a small pin 25. It will be understood from the construction above described that the lever 11, while adjustably fulcrumed on the base, is permanently coupled with the same through the engagement of the ends of the trunnion pin 105

with the apertures in the bearing bosses. This feature permits the liner to be carried as a unit by the lever as a handle, and prevents misplacement of either part of the liner.

While the longitudinally spaced bearing seats 18 and 19 in the base 10 are in the same horizontal plane in the embodiment of the invention above described, an arrangement of the seats with one in a plane above the other is also contemplated and comes within the spirit of the invention. It might be desirable, for instance, to have the rear bearing seat rather low to permit of a lifting purchase on the rail at a great leverage whereby to first loosen the rail from its bed, and have the front bearing seat higher to permit of the proper shifting purchase on the rail after the same has been loosened and is consequently in a condition to be more readily moved. Such a modified arrangement of the seats is shown in Fig. 7.

The manner in which the track liner is used, may be briefly described as follows:

When a rail, for instance, is to be shifted, the liner is placed on the ballast between two of the ties with the bosses 17 of the base 10 against the head of the rail, as shown in Fig. 4. The lips 14 of the liner are then forced into the ballast and under the lower edge of the rail by means of a crowbar or other suitable rod, as shown in Fig. 4, thus placing the liner in the position shown in Fig. 5. The crowbar is then inserted in the socket 23 of the lever 11, and the rail is shifted a short distance relative to the base 10, as shown in Fig. 6. The trunnions 24 of the lever are then swung from the rear bearing seats 18, as shown in Fig. 5, to the front bearing seats 19, as shown in Fig. 6, and the rail is again shifted. By the provision of the adjustable fulcrum for the lever 11 on the base 10, the proper leverage may still be applied horizontally to the rail after the latter has been moved out of the effective range of the lever when in its original fulcruming position, and any necessity of resetting the base 10 for each small movement of the rail is accordingly eliminated.

I claim:

1. A track liner comprising a base having two spaced lips at one end of the bottom of the same and two spaced bosses above the lips, and a lever positioned between the lips and between the bosses and having a fulcruming portion for pivotal co-action with the bosses, said bosses partially overhanging said lips whereby to provide room for the reception of the base of a rail beneath the bosses.

2. A track liner, comprising an elongated base having two spaced lips at one end of the bottom of the same and two spaced bosses above the lips, and a lever positioned between the lips and between the bosses and having a fulcruming portion for pivotal co-action with the bosses in any one of a plurality of positions longitudinally of the base, said lips being substantially flat whereby to permit the same to be inserted beneath the base of a rail far enough to bring the portion of the lever between the lips against the base of the rail while in a position substantially perpendicular to the lips.

3. A track liner, comprising a lever, and an elongated base having an upper portion adjacent one end for fulcruming the lever and a substantially flat supporting bottom which is bifurcated adjacent the same end to form spaced lips between which the lower end of the lever extends, said bottom being curved adjacent the bifurcation about a center adjacent the fulcruming portion to give the lips rearwardly increased taper and additional body below the fulcruming portion.

4. A track liner, comprising an elongated base, a superstructure on the base having a plurality of fulcruming seats above the front end of the base, and a lever having a fulcrum which may be shifted from one seat to another, said superstructure receding below the fulcruming seats away from the front end of the base, whereby to permit a portion of the lever below the fulcruming point to engage perpendicularly with the edge of a rail when the lever is in an upright position and fulcrumed in the seat most removed from the front end of the base.

5. A track liner, comprising an outspread base, a superstructure on the base having two longitudinally spaced fulcruming seats of different heights which are connected from above by a slot, and a lever having a transversely disposed fulcrum which fits into either of the seats and is movable from one to the other through the slot while in locked association with the structure.

6. A track liner, comprising an outspread base having two fulcruming seats spaced longitudinally of the liner with the front seat higher than the rear seat, and a lever having a fulcrum which may be shifted from one seat to another and a rail-engaging portion which is designed to engage with and operate on the edge of a rail at a point beneath the particular seat in which the lever happens to be positioned.

In testimony whereof I have hereunto subscribed my name.

RALPH H. BLOXHAM.
